UNITED STATES PATENT OFFICE.

THOMAS F. GRAHAM, OF BRADDOCK, PENNSYLVANIA.

STEEL-REINFORCED-CONCRETE FENCE.

1,247,107.

Specification of Letters Patent. Patented Nov. 20, 1917.

Application filed September 2, 1914. Serial No. 859,809.

To all whom it may concern:

Be it known that I, THOMAS F. GRAHAM, a citizen of the United States, and resident of Braddock, in the county of Allegheny 5 and State of Pennsylvania, have invented certain new and useful Improvements in Steel-Reinforced-Concrete Fences, of which the following is a specification.

My invention relates to the construction 10 of fences and more particularly relates to fences constructed of reinforced concrete having novel means whereby the several parts of the fence are connected and held in interlocking engagement.

15 One object of my invention is to provide a concrete fence structure having novel means whereby a strong and durable fence is obtained with a minimum amount of material, and whereby liability of cracking or 20 other damage by reason of settling or climatic changes is avoided and overcome.

Another object of the invention is to provide a fence structure formed of steel reinforced concrete which is easily and quickly 25 made and in the manufacture of which the cost of erection is materially lessened.

Another object of the invention is to provide a concrete fence having the novel combination and arrangement of parts herein- 30 after described in detail and specifically pointed out in the appended claims.

Referring to the accompanying drawing forming part of this specification, Figure 1 is a longitudinal side elevation showing 35 a portion of a fence constructed and arranged in accordance with my invention.

Fig. 2 is a transverse sectional elevation of the same, the section being taken on the line II—II of Fig. 1.

40 Fig. 3 is an end elevation of the posts forming part of my invention and showing the rabbets or recesses in the side faces thereof.

Fig. 4 is a detail sectional plan, the section being taken on the line IV—IV of Fig. 1 illustrating the manner of reinforcing the concrete of the posts and of interlocking the panels to posts of the fence.

45 In the drawing the numeral 2 designates a foundation wall which extends along the base of the fence, the top of this wall usually being located at or slightly above the ground line.

Positioned at suitable intervals in the 50 length of the wall are vertically extending posts 3 which as shown, are rectangular in

cross section and have an inwardly tapering recess or groove 4 in each of two opposite sides thereof, these grooves having inwardly inclined side faces 5—5 extending lengthwise for substantially the entire length of the post that is above the top of the foundation 2.

A metal beam 6 (a T rail being form of beam shown) is embedded in the concrete 60 posts, this beam extending downwardly into the foundation wall 2.

The posts are provided with caps 7 which are held in place by means of a series of metal pins 8, the pins being embedded in 70 the posts projecting upwardly into the caps.

Between each pair of adjacent posts is a concrete panel 9 which is provided with tongues 10 that extend into the recesses or grooves 4 in the sides of the posts to retain the panel in place. The panels 9 are reinforced with metal in any desired manner, the reinforcing wire 12 shown, (a product made especially for reinforcing concrete work) usually being employed.

80 In constructing the fence, the foundation wall 2 is first formed with the vertical metal reinforcing members 6 of the posts 3 erected at suitable intervals in the length of the wall. A form is then built around each of the metal beams 6 and the concrete is poured into the forms. After the concrete has become set the forms are removed. When the posts 3 have set forms for making the panel 9 are set up and after the reinforcing wire 90 10 is placed in the form, the panel is poured. In pouring the panels provision is made for preventing a bond being formed along the lower edge 11 of the panels with the foundation wall and provision is also made 95 to prevent bonding between the meeting faces of the panels 9 and posts. One way of securing this result is to whitewash or paint the surfaces of the foundation and the posts which contact with the panels before the panels are poured.

100 When a panel 9 becomes set it contracts and pulls away slightly from the posts 3 and the so formed clearance between the tongues 10 of the panels and the grooves 4 in the posts provides for expansion and contraction, and in this way avoids possible cracking of the fence which will otherwise occur by reason of uneven settling or variations in atmospheric conditions.

110 After the panels 9 are formed between the posts 3 the caps 7 which preferably are

formed beforehand in a suitable mold are placed on top of each post, the pins 8 embedded in the top of the posts entering suitable holes in the lower faces of the caps 5 to prevent sidewise movement of the caps relative to the posts while the weight of each cap will be sufficient to maintain it in position.

The advantages of my invention will be 10 appreciated by those skilled in the art. My improved fence construction is simple and is easily and cheaply made. By the provision of a loose connection between the foundation wall and panels and the posts 15 the expansion occurring in the wall is provided for and liability of cracking of the fence is avoided and prevented.

The metal reinforcing member in each post provides a rigid connection between the 20 posts and the foundation wall.

Modifications in the construction and arrangement of the parts may be made without departing from my invention.

The foundation may be made to extend 25 but a short distance beyond each post or may be omitted entirely when found necessary or desirable and other changes may be made within the scope of the appended claims.

80 I claim:

1. In a fence, the combination of a series of lengthwise vertical concrete posts, said posts each having a metal beam embedded therein to rigidly secure the fence in upright position, and opposite faces of said 35

posts having grooves with closed ends therein, and a metal reinforced concrete panel between adjacent posts, said panel being molded *in situ* and having tongues on the ends thereof projecting into said groove to fasten 40 the panels in place, and means between the meeting surfaces of said posts and panels to prevent bonding thereof in forming the panels and loosely secure the panels in upright position between the posts.

45 2. In a fence, the combination of a concrete foundation, a series of lengthwise vertical concrete posts located at intervals in the length of said foundation, said posts having a metal beam embedded therein and 50 the beams extending downwardly beyond the lower end of the concrete posts into said foundation to rigidly secure the fence in upright position, said posts having recesses with closed ends in opposite faces thereof, 55 and metal reinforced concrete panels between adjacent posts, said panels being formed *in situ* and having tongues on the ends thereof projecting into said recesses, and means between the contacting surfaces 60 of the posts and panels adapted to prevent bonding thereof in forming the panels and arranged to loosely secure the panels in upright position between the posts.

In testimony whereof, I have hereunto set 6 In testimony whereof, I have hereunto set 6 my hand.

THOMAS F. GRAHAM.
